MULLION CENTER

Filed April 4, 1928

Inventor
Oscar Schield,

By Clarence A. O'Brien,
Attorney

UNITED STATES PATENT OFFICE

OSCAR SCHIELD, OF MEDFORD, WISCONSIN

MULLION CENTER

Application filed April 4, 1928. Serial No. 267,339.

The present invention relates to improvements in window frame constructions and has reference more particularly to a mullion center.

5 One of the salient objects of the present invention is to provide a mullion center wherein the inner side edges of the blind stops are formed with tongues for interfitting relation with the respective grooves formed in 10 the side edges of a filler member whereby cold air is prevented from entering the room thereby providing an air-proof window frame.

One of the important objects of the present invention is to provide an improved mullion center which includes a filler member, means being provided at the side edges of the filler for interlocking engagement with the opposite blind stops or rails, the filler being 20 further of such construction as to afford an air space between the outer front side of the filler and the outer casing of the window frame.

A further object is to provide a mullion center which is simple in construction, inexpensive, strong and durable and further well adapted to the purposes for which it is 25 designed.

Other objects and advantages will become 30 apparent during the course of the following description.

In the accompanying drawing, forming a part of this specification, and in which like numerals indicate like parts throughout the 35 same:

Figure 1 is a horizontal sectional view through a mullion center showing my improved filler in position, and

40 Figure 2 is a vertical sectional view for more clearly illustrating the beveled lower edge of the filler that engages with the upper face of the window sill.

In the drawing wherein for the purpose 45 of illustration is shown the preferred embodiment of my invention, the numeral 1 designates generally a portion of a mullion center of a window frame, the same including a sill member 2 which is disposed at an incline and extending upwardly from the sill member 2 are the vertical walls 3 and 4 re-

spectively the same being arranged in spaced relation. Vertically disposed blind stops or rails 5 and 6 are arranged adjacent the forward edges of the respective side walls, the forward edges of the side walls being formed 55 with tongues that engage within suitable grooves or notches formed in the rear faces of the respective blind stops as shown generally at 7 in Figure 1. The inner opposed faces of the blind stops are formed with the 60 longitudinally extending tongues 8 and 9 respectively and the purpose thereof will be presently apparent.

The outer front faces of the blind stops or rails terminate flush with the shoulder 10 65 formed in the upper face of the inclined sill member 2 at the forward edge portion thereof and the outside casing 11 is adapted to be disposed against the front faces of the forward blind stops or rails and the lower edge of 70 this casing is beveled to properly engage with the inclined upper face of the sill member and furthermore the lower portion of the window frame casing will abut against the shoulder 10. 75

Additional blind stops 12 and 13 are arranged rearwardly of the forward blind stops 5 and 6 in spaced relation thereto to form channels for receiving the sliding window sashes not shown, and these rear window sash 80 stops are set in suitable cutout portions formed in the outer faces of the side walls as clearly disclosed in Figure 1.

The invention comprehends the provision of a filler 14 that is disposed between the forward sash rails 5 and 6 and the side edges of this filler are formed with longitudinally extending grooves or channels 15 and 16 respectively to receive the tongues 8 and 9 whereby to provide an interlocking connection 90 between the blind stops 5 and 6 and the filler.

The lower edge of the filler member 14 is beveled whereby to properly rest upon the inclined sill member 2 and it will be observed 95 that the front face of the filler is cut out to form an air chamber 17 between the casing 11 and the filler.

The simplicity of my invention enables the parts to be readily and easily assembled and a 100

strong and durable construction will be provided.

While I have shown the preferred embodiment of my invention, it is to be understood that various changes in the size, shape and arrangement of parts may be resorted to without departing from the spirit of the invention and the scope of the appended claim.

Having thus described my invention, what I claim is:—

10 In a mullion center for window frames, a sill, a pair of spaced side walls extending upwardly therefrom, blind stops at the forward edges of the respective side walls, co-operating blind stops extending from the outer sides of the walls rearwardly of the first mentioned blind stops, an outer casing for resting upon the sill and disposed adjacent the front faces of the forward blind stops, a filler member disposed between the forward blind stop, the side edges thereof being formed with longitudinally extending grooves, tongues formed on the inner opposed side edges of the forward blind stops for co-operation with the respective grooves to afford an interlocking connection between the front blind stop and said filler member, the front side of the filler member being cut-out to provide a space between the filler and the adjacent side of the outer casing.

30 In testimony whereof I affix my signature,
OSCAR SCHIELD.
